APPARATUS FOR BURNING POWDERED FUEL

Durbin Van Law, Denver, Colo., assignor to
Powdereco, Inc., Denver, Colo.

Application December 27, 1932, Serial No. 649,008

8 Claims. (Cl. 110—28)

This invention relates to apparatus for burning powdered fuel, and more particularly to certain new and useful improvements in the constructions disclosed in my application for Patent 5 Serial No. 593,006, filed February 15, 1932.

It is an object of the present invention to promote the efficiency of the burner shown and described in the above-mentioned application for patent by novel details of construction and a 10 novel arrangement of parts, as will be fully disclosed in the course of the following description, and another object is to provide for the use of the burner, in cooperation with a source of fuel-carrying air currents.

In the accompanying drawings, in the several views of which like parts are similarly designated,

Figure 1 represents a sectional elevation of the improved burner in its operative position relative to the feed opening in the wall of a furnace.

Figure 2 is a partially broken front view of the same looking in the direction of the arrow 2 in Figure 1.

Figure 3 is a fragmentary section on the line 3—3 of Figure 1.

Figure 4 is a sectional view of a modification of the construction shown in Figure 1.

Figure 5 is a partially sectional front elevation of the construction shown in Figure 4.

Figure 6 is an elevation drawn to a reduced scale, showing the burner in cooperative association with a source of fuel-laden air currents.

Occupying an opening of the furnace wall, is a combustion chamber 5 made up of a conical and annular body 6 of refractory material, such as fire brick, surrounded by a bed of rockwool or other suitable insulating substance 7 within a thin metal tube 8, which is fitted in the opening.

A flanged plate 9 of similar material covers the front end of the heat resisting body and the surrounding insulation, and an annular plate 10 covers the insulating material and a part of the body at the inside of the wall.

The combustion chamber thus constructed has an opening 12 aligned with a passage 13 in the furnace wall for the discharge of ashes.

The inner surface of the refractory body of the combustion chamber flaring to the inner surface of the furnace wall, has at its opposite end a chamber 14 of comparatively narrow width.

A burner is spaced from this chamber to provide a passage 15 for air from the chamber 14 into the preliminary combustion chamber.

The burner comprises a body or block 16 of terra 55 cotta or other refractory material mounted in a

housing 17 which is fastened to and exteriorly of the furnace wall by bolts 18.

The housing is hollow to provide an air-chamber 19, and it has in its outer surface screen-covered ports 20 communicating with the chamber, the effective size of which is controlled by a revolving shutter 21. At the lower portion of the housing is a valve chamber 22 in which is fitted a rotary three-way valve 23.

This valve may be rotated from outside the housing by a tool inserted in cavities 23a, and it may be held in adjusted positions by a setscrew 24. The valve chamber has a port 25 communicating with the air-chamber 19 which connects with the passage 15 between the burner and the combustion chamber. The valve chamber also has a port 26 for the admission of air from the surrounding atmosphere and it has a third port 27 which connects by means of a flexible conduit 28 with a source of fuel-carrying air current, such as the grinding mill shown at 29 in Figure 6 of the drawings.

The valve has three intercommunicating peripheral openings 30, 31 and 32 adapted to register with the port of the housing.

The burner-block has a central opening 33 into which extends a flaring feed nozzle 34, which at its smaller end connects with a conduit 35 connecting with the source of fuel-carrying air currents exemplified by the before-mentioned mill.

A packing 36 of non-conductive material surrounds the nozzle inside the burner-block. At the end of the nozzle inside the block, is a whirler in the form of radial fan-like blades 37, and opposite to the nozzle and the whirler the block has a flaring opening 38 through which the fuel-laden air currents pass into the combustion chamber. Inside the flaring openings are the terminals of two conductors of electricity 39, spaced apart to provide a spark-gap 40.

The conductors extend through openings in the block which are enlarged as at 41 to receive couplings 42 by means of which the conductors are connected with lead wires 43. Openings 44 communicating with the enlargements 41 afford access to screws of the couplings from outside the burner and its housing.

In the modification shown in Figures 4 and 5, a supplemental ignition means is provided by a circular pipe 45 disposed inside the air-chamber, in connection with a source of supply of gaseous fuel. The ring 45 has a number of nozzles or burner-openings 46, facing the passage 15 leading to the preliminary combustion chamber 5.

In the operation of the burner-system, air-cur-

rents carrying finely divided coal or other fuel are conducted through the conduit 35 into the nozzle 34 at a velocity predetermined in the grinding mill or other source. The flaring nozzle, 5 the flaring passage 38 of the burner, the flaring combustion chamber 5, and the whirler 37 co-operate to gradually reduce the velocity of the air currents so that the fuel enters the combustion chamber of the furnace at a comparatively low 10 velocity, which is important since it produces the short flame essential in small furnaces, such as those used in residential heating-systems.

During the passage of the fuel through the burner, it is ignited by the spark in the gap 40 15 or by the flames issuing from the gas-ring 45. The gas-ring is provided particularly for use in case the coal or other fuel is of low volatile character, to insure its ignition before it enters the combustion chamber. In this instance, the spark 20 will ignite the gas and the flames of the burning gas ignite the coal.

In the use of fuel of higher volatility, the electric spark is sufficient, in itself, to ignite the fuel.

Air in regulatable quantities is admitted to the 25 fuel entering the combustion chamber through the valve-controlled ports 20, which communicate with the air-chamber 19 around the burner, and by means of the passage 15 with the combustion chamber. Additional air may be admitted to the air chamber through the ports 26 30 and 25 when the valve is in the position shown in Figure 3 of the drawings.

The port 27 of the valve housing communicates with the suction line of the source of fuel supply 35 so that a surplus of heated air may be drawn from the combustion chamber to the source for the purpose of preheating the fuel, and of aiding in conveying the fuel to the burner by a current of air. Thus a circulatory movement of the air 40 between the source and the combustion chamber is produced.

It will be understood that by further adjustment of the valve, the air-chamber 19 around the burner, may be shut off from the atmosphere 45 at 26, and from the source of fuel-supply.

The valve 23 and the shutter 21 provide means for absolute control of the operation of the burner, and owing to the connections between the combustion chamber and the source as hereinbefore 50 described, the suction of the source may be utilized to regulate the supply of secondary air to the burner. The air chamber around the burner insulates the latter from the housing in which it is mounted.

55 The connection between the combustion chamber and the source by way of the valve 23, will harmlessly dispose of the effects of minor ignition explosions and the resulting dust and dirt by sucking the gases back into the mill. It, moreover, lessens the cooling effect of the air upon the ports of the burner system. The fuel ignited in the burner block 16 enters the combustion chamber in a burning condition. The comparatively thin body 6 of the combustion chamber 60 quickly heats and continues combustion, and the fuel thus enters the combustion chamber of the furnace in a state of combustion throughout, and at the desired low velocity. It is essential that the velocity of the air currents shall not be 65 below that at which the fuel carried by the currents may fall by lack of a sustaining force.

What I claim and desire to secure by Letters Patent is:

75 1. A burner-system for furnaces, having a combustion chamber, a source of fuel-carrying

air currents, a burner communicating with the combustion chamber, a conduit establishing communication between the burner and the source, a conduit for returning heated air-fuel mixtures from the burner to the source, having an opening to the atmosphere, and a three-way valve controlling the last named conduit so as to selectively connect the burner with the atmosphere or with the source. 5

2. A burner-system for furnaces, having a 10 combustion chamber, a source of fuel-carrying air currents, a burner communicating with the combustion chamber, the burner having a central inwardly flaring opening for the admission of fuel, a conduit providing a communicating passage between the opening and the source, means providing an annular chamber about the burner in communication with the space about the discharge end of the flaring opening, a separate conduit forming a communicating passage between 15 the annular chamber and the source, and means for selectively establishing communication from the annular chamber to the source, or to the atmosphere. 20

3. A burner-system for furnaces, having a 25 combustion chamber, a source of fuel-carrying air currents, a burner communicating with the combustion chamber, the burner having a central inwardly flaring opening for the admission of fuel, a conduit providing a communicating passage between the opening and the source, means providing an annular chamber about the burner in communication with the space about the discharge end of the flaring opening, a separate conduit forming a communicating passage between 30 the annular chamber and the source, and means for selectively establishing communication from the annular chamber to the source, or to the atmosphere. 35

4. A burner system for furnaces comprising a 40 furnace wall having an opening whose inner end is in communication with the interior of the furnace, a tubular member forming a combustion chamber and having one end in communication with the interior of the furnace through said 45 opening, a burner in communication with the other end of the tubular member and spaced therefrom to provide a passage for air to the combustion chamber, a housing surrounding the burner having an air chamber in communication 50 with said passage, and having a branched conduit in communication with the chamber, means for connecting the air chamber with either branch to the exclusion of the other, a source of fuel-carrying air, one of the branches communicating directly with the atmosphere, a conduit for establishing communication between the other branch and the source of fuel-carrying air, and a third conduit for establishing a communication between the source and the burner for 55 conveying fuel-carrying air to the burner. 60

5. In a system for burning finely divided fuel, a burner having a combustion chamber, a source of fuel-carrying air, a conduit extending from the source to the burner for conveying fuel-carrying 65 air to the latter, a housing providing an air chamber about the burner and a passage establishing communication between the air chamber and the combustion chamber, and means including a conduit and a three-way valve for selectively connecting the air chamber to the atmosphere to the exclusion of the source and to the source exclusive 70 of the atmosphere. 75

6. A burner-system for furnaces, comprising a furnace wall having an opening, a combustion 75

chamber having one end communicating with the interior of the furnace through said opening of the furnace-wall, a burner communicating with the combustion chamber at the other end thereof, and spaced therefrom to provide a passage for air to the combustion chamber, a housing surrounding the burner having an air chamber in communication with said passage, and having two conduits communicating with the atmosphere, a valve controlling one of said two conduits, a source of fuel-carrying air-currents, means establishing communication between said source and the burner, a conduit to return fuel and air from the housing to the source, and a valve controlling the last-mentioned conduit and the other of said two conduits.

7. In a system for burning finely divided fuel comprising a burner, having a combustion chamber for the fuel, a source of fuel-carrying air-currents connected with the combustion chamber of the burner, means including a conduit having a branch effective to connect the combustion chamber to atmosphere for the supply of air and a branch effective to connect the combustion

chamber with said source, for the escape of heated air-fuel mixtures to the source and a valve operable in one position to open one of said branches and operable in another position to open the other of said branches.

8. A burner-system for furnaces, comprising a burner having a combustion chamber, a source of fuel-carrying currents, communicating with said combustion chamber, a housing surrounding the burner and communicating with the combustion chamber thereof, and having a conduit establishing communication between the burner and the source, another conduit for returning air-currents from the housing to the source, provided with an opening to the atmosphere, and a three-way valve controlling the conduit from said housing to said opening and the source so as to selectively connect the housing with the source and to exclude the opening, to connect said housing with the source and to include the opening and to connect said housing with said opening and to exclude the source.
